(57) **CLAIM**

The ornamental design for a camera cover, as shown and described.

DESCRIPTION

FIG. 1 is an isometric view of a camera cover incorporating our new design, viewed from above, in front of, and from the left side of the camera cover;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawings located immediately adjacent to shaded areas represent the bounds of the claim and form no part thereof. All other broken lines depict portions of the camera cover that form no part of the claimed design.
